UNITED STATES PATENT OFFICE.

WILLIAM S. GUTHRIE, OF TERRELL, TEXAS.

TIME CIRCUIT-CLOSER.

No. 840,562.

Specification of Letters Patent.

Patented Jan. 8, 1907.

Application filed August 29, 1905. Serial No. 276,233.

To all whom it may concern:

Be it known that I, WILLIAM S. GUTHRIE, a citizen of the United States, residing at Terrell, in the county of Kaufman and State of Texas, have invented a new and useful Time Circuit-Closer, of which the following is a specification.

The present invention relates to improvements in that class of systems wherein the movements of one or more secondary clocks are controlled and regulated by a master-clock.

One of the principal objects is to provide a novel and comparatively simple system, wherein a number of clocks can be operated by a single electrical battery, the movements of such clocks being periodically effected through the medium of an automatic circuit-closer controlled in a novel and effective manner by a master time-movement or clock.

The preferred embodiment of the invention and a modification of the secondary clock structure are illustrated in the accompanying drawings, wherein—

Figure 1 is a front elevation of a master and a secondary clock, showing the connections between the same diagrammatically. Fig. 2 is a detail view of the circuit-closer and controlling means therefor, showing the parts in a position just prior to the operation of the circuit-closer. Fig. 3 is a view similar to Fig. 2, but showing the circuit-closer released. Fig. 4 is a sectional view through the secondary clock illustrated in Fig. 1. Fig. 5 is a side elevation of said clock. Fig. 6 is a detail sectional view taken substantially on the line 6-6 of Fig. 4. Fig. 7 is a side elevation of a modified form of secondary clock. Fig. 8 is a sectional view therethrough. Fig. 9 is a diagrammatic view of another slight modification of the invention.

Similar reference-numerals designate corresponding parts in all the figures of the drawings.

In the embodiment illustrated the circuit-closer and master time-movement are designated generally by the reference-numeral 9, while a single secondary clock is shown generally at 10. The master-clock consists of a suitable frame 11, in which is mounted an ordinary time-movement consisting of a driving-spring 12 and train of gearing 13, terminating in the usual escapement-wheel 14 and cooperating dog member 15. In the

present embodiment one of the wheels 16 of 55 the train of gearing 13 is arranged to rotate once a minute and is carried upon an arbor 17, said arbor also carrying a cam 18, which cam thus has a complete revolution once every minute.

Mounted in the frame 11 is a circuit-closing device which comprises a stationary contact element 19, supported on an insulating-block 20, that is secured, as shown at 21, to one corner of the frame, this contact element 65 being held in place on the block 20 by a binding-screw 22. Coöperating with the stationary contact element is an oscillatory contact element consisting of an arm 23, pivotally mounted between its ends in the frame, 70 as shown at 24, and carrying at one end a leaf-spring 25, the free terminal of which is movable into and out of engagement with the stationary contact element 19. It will be noted that the secured end of the spring 75 25 is located in rear of the terminal of the arm and that said terminal is free and is located beneath the free portion of the spring contiguous to the portion that engages the element 19. A spring 26 normally holds the 80 arm 23 in a position to maintain the contact-spring 25 out of engagement with the contact element 19. The oscillatory contact element is arranged to be automatically operated by a motor consisting of a driving-spring 27, operating upon a train of gearing 28, journaled in the frame 11 at one side of the time-movement, said train of gearing including an arbor 29, that carries a wheel 30, having peripheral teeth 31. The lower end 90 of the swinging arm 23 of the oscillatory contact element is downturned and tapered, as shown at 32, being arranged to ride over the teeth 31 of the wheel 30 and being, furthermore, yieldingly held in engagement with 95 said teeth by the spring 26.

The train of gearing of the circuit-closer motor, furthermore, includes a gear-wheel 33, having stop projections 34 on one side, said wheel meshing with the pinion 35 of a fan 36. 100 A detent is employed for normally holding the motor, and consequently the circuit closer, against movement. This detent consists of a pivot-shaft 37, journaled in the frame and carrying an arm 38, provided with 105 an offset free terminal 39, that rides upon the cam 18 of the time-movement shaft 17. The pivot-shaft 37, furthermore, has rigidly se-

cured thereto a pair of dogs, consisting of arms 40 and 41, the arm 40 having a depending free terminal 42, that is movable into and out of the path of movement of the projections 34 of the motor-wheel 33. The other arm 41 has an offset free terminal 43, which in like manner is movable into and out of the path of movement of the fan 36.

It is believed that the operation of the master-clock can now be made plain, it being first stated, however, that the swinging contact-spring 25 is in electrical communication with a suitable binding-post 44, grounded upon the frame 11. Under normal conditions the terminal 42 of the dog 40 of the detent is located behind one of the projections 34 of the wheel 33 of the circuit-closer motor. Consequently said motor is held against movement, and when so held the contact elements are out of engagement, as the terminal 32 of the swinging contact element is located between the teeth 31 of the wheel 30. The wheel 16, and consequently the arbor 17, carrying it, as already stated, is revolved once in every minute, and therefore as the cam 18 is correspondingly rotated the arm 38 will be gradually depressed until the terminal 42 of the dog 40 is raised above the projection 34. The circuit-closer motor is thereupon released; but the elevation of the dog 41 with the dog 40 carries the terminal 43 into the path of movement of the fan 36, so that the circuit-closer motor is again stopped, as illustrated in Fig. 2. As the cam 18 continues to revolve, however, its part of greatest diameter will finally pass the offset portion 39 of the arm 38, whereupon the dogs 40 and 41 will again drop, being actuated by the spring 38^a. This immediately releases the fan, and consequently the motor, permitting the wheel 33 to have one-half of a revolution, whereupon the succeeding projection 34 will engage the offset terminal 42 of the dog 40. During this one-half revolution of the wheel 33 the toothed wheel 30 will be partially rotated. In other words, it will be moved sufficiently far to carry one of the teeth beneath the offset terminal 32 of the arm 33. As a result said arm will be swung, and the spring 50 will be brought into engagement with the contact element 19, thus closing an electrical connection between the binding-posts 44 and 22. The terminal 32 will, however, drop into the space between the succeeding teeth, and the contact will be again broken, thus leaving the parts in the positions originally described, and shown in Fig. 1, from which positions they will be again operated by a continued rotation of the cam. The action of the contacts during this automatic operation is peculiarly effective. In closing the circuit on the downward movement of the arm 23 the spring will engage the element 19 before the arm has fully ac-

complished its movement. The result is 65 that the spring has a sliding engagement with the contact 19, serving to maintain the surfaces in clean and bright condition, and thereby insuring effective electrical contact between them. A further advantage resides 70 in the fact that the free end of the arm will be carried away from the spring, as shown in Fig. 3, and consequently when the terminal 32 of said arm is passed by the tooth of the wheel 30, that has moved said arm, the 75 spring 26 will quickly return the arm, and the free end of said arm will strike the spring 25 with considerable force, and thereby cause an exceedingly-rapid separation of the contacts. 80

One embodiment of the secondary clock is illustrated in Figs. 1, 4, 5, and 6. In this embodiment a simple frame 45 is employed, in which is journaled an arbor 46, carrying a minute-hand 47 and also carrying a ratchet-wheel 48, provided with sixty teeth 49. The hand 47 is preferably counterbalanced by a weight 50. An hour-hand 51, carried by a sleeve 52, loosely journaled on the shaft 46, is suitably geared to said shaft, as shown at 53. 90

For the purpose of actuating the ratchet-wheel 48, and consequently the hands, a double electromagnet 54 is suitably mounted in the frame 45, and coöperating with the poles 55 thereof are swinging armatures 56, 95 carried by a shaft 57. This shaft has rigidly fixed thereto an arm 58, on which is pivoted a weighted actuating-pawl 59, that acts upon the teeth 49 of the ratchet-wheel. The movement of the shaft 57 is limited by a finger 60, secured to said shaft and engaging one edge of the frame, as illustrated in Fig. 5. A stop-pawl 61 is loosely journaled on the shaft 57 and has an offset tooth 62, movable into and out of engagement with the wheel 48 between the teeth thereof. The pawl is yieldingly urged into such engagement by a spring 63, secured thereto and to one of the armatures 56, but is normally held out of such engagement by the outer end 64 of the arm 58, carrying the actuating-pawl 59. Another pawl 65, pivoted upon the frame and yieldingly held in engagement with the ratchet-wheel by a spring 66, prevents retrograde movement on the part of such wheel. The means for energizing the magnets 54 is a battery, (shown diagrammatically at 67,) said battery having one pole connected to the electromagnets of a lead 68, the other pole being connected to one of the binding-posts 22 of the master-clock by a lead 69. The other binding-post 44 of said master-clock is connected to the electromagnets by a lead 70, and thus the circuit is completed when the contact elements 19 and 20 are engaged. 115

It is now thought that the operation of the system may be readily comprehended. Every minute the electric circuit is closed in the

master-clock, as already fully described. Consequently the magnets 54 will be energized. This will cause the armatures 56 to swing, causing the pawl 59 to operate and move the ratchet-wheel 48 the distance of one tooth. This will move the hand 47 one-sixtieth of a revolution, or, in other words, the distance of a one-minute space. When the arm 58 moves inwardly to carry the pawl 59 to actuate the ratchet-wheel, the outer end of the arm 64 will of course swing inwardly. This will permit the spring 63 to act upon the stop-pawl 61, so that the tooth 62 will be carried into engagement with the wheel, and the overthrow of said wheel will be positively prohibited. As soon as the contact is again broken in the master-clock the armatures will return to their normal positions, the stop-pawl 61 will be disengaged from the wheel by the return of the arm 58, and the actuating-pawl will ride over a single tooth of the wheel and take the proper position to again actuate the same. It will thus be seen that a plurality of electrically-operated secondary clocks of simple structure can be effectively controlled from a master-clock, which master-clock includes an automatically-operated circuit-closer of novel structure separate from the time-movement and controlled thereby. It will of course be understood that while only one secondary clock is shown in the present system any desired number may be employed, depending on the strength of the battery or other source of electrical energy. Furthermore, while the hands of the secondary clocks in the present embodiment are moved once in every minute it will be readily seen that by simple and obvious alterations of the gearing the periodicity of movement may be changed as desired.

A slight modification of the secondary clock is illustrated in Figs. 7 and 8, the only difference being in the electromagnet and armature. The other parts have therefore been given the same reference-numerals as those employed in Figs. 4 and 5. A single electromagnet 54^a is provided in the modification, which magnet has a pole 55^a, co-operating with a flat armature 56^a, that is secured to the shaft 57. Otherwise the structure and the operation are exactly the same as in the embodiment already set forth, and any further description thereof is believed to be unnecessary.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention. Thus the motors of the

master-clock may be run by weights instead of springs, as will be apparent, and while they are shown as located in a single frame it will be apparent that separate frames for each motor may be employed, the specific mountings not being particularly important. In this connection attention is invited to Fig. 9, wherein a time-movement 10^a is shown having a cam 18^a. A separate motor-operated circuit-closing device 19^a is also shown, the time-movement and circuit-closing device being substantially the same as those already described, except that they are separately mounted in a common casing 20^a. The detent for the motor 19^a consists of an arm 38^a and arms 40^a and 41^a, corresponding in all respects to the detent of the first-described embodiment. In this structure, however, the cam 18^a operates a lever 42^a, fulcrumed between its ends, one end of said lever being connected by a link or wire 43^a with the arm 38^a. It will be apparent that this structure operates the same as the first-described embodiment. Furthermore, the master-clock can be employed as a circuit-closing device for periodically operating any variety of devices wherein a circuit-closing device of the character herein described may be used and is not necessarily limited to employment in connection with secondary clocks.

Having thus described my invention, what I claim as new, and desire to secure by Letters Patent, is—

1. In mechanism of the class described, the combination with a circuit-closer comprising contact elements, a swinging arm, a contact-spring secured to the arm between the ends thereof, one of the ends of said arm being free and disposed longitudinally of the spring, said spring moving into and out of sliding engagement with the contact element upon the movement of the arm, and the end of said arm being movable away from and against the spring to effect its disengagement from the contact element, a motor for effecting the swinging movement of the arm, means for holding the motor against movement, and means for intermittently releasing the motor.

2. In mechanism of the class described, the combination with a circuit-closer comprising a contact element, a swinging arm pivotally mounted between its ends, a contact-spring secured to the arm between the ends thereof, one of the ends of the arm being free and disposed longitudinally of the spring, said spring moving into and out of sliding engagement with the contact element upon the movement of the arm and said free end of the arm being movable away from and against the spring to effect the rapid disengagement of the latter from the contact element, a motor having an element that en-

gages the other end of the arm to that associated with the spring for effecting the movement of the arm, a detent for holding the motor against movement, and means for intermittently actuating the detent and thereby permitting the intermittent movement of the motor.

In testimony that I claim the foregoing as my own I have hereto affixed my signature in the presence of two witnesses.

WILLIAM S. GUTHRIE.
